UNITED STATES PATENT OFFICE.

BERT E. ROCKHOFF, OF DETROIT, MICHIGAN, ASSIGNOR TO LEONARD A. YOUNG, OF HIGHLAND PARK, MICHIGAN.

BORDER-STRIP FOR SPRING-CUSHIONS.

1,203,051.

Specification of Letters Patent. Patented Oct. 31, 1916.

Application filed April 29, 1916. Serial No. 84,809.

To all whom it may concern:

Be it known that I, BERT E. ROCKHOFF, a citizen of the United States, residing at Detroit, county of Wayne, State of Michigan, have invented a certain new and useful Improvement in Border-Strips for Spring-Cushions, and declare the following to be a full, clear, and exact description of the same, such as will enable others skilled in the art to which it pertains to make and use the same, reference being had to the accompanying drawings, which form a part of this specification.

This invention relates to seat cushion frames for spring seat-cushions.

The specific object in view is a seat spring for an automobile seat, having a bottom frame which will not only serve to hold the springs along the borders but also serve to 20 detachably hold the upholstering skirt.

It is the object of this improvement to so clamp the upholstering skirt in place that in case for any reason it is desired to change the upholstering skirt or take it out for re-25 pair, it may be readily accomplished. This cannot very successfully be done with the single-piece clamping strips which are made of very heavy gage steel and which when once clamped in place cannot very success-30 fully be pried open to take the skirt out without tearing the skirt. The border strips which carry tacking strips are objectionable because when the skirt is tacked on, it re-35quires the removal of several tacks to get the skirt off, and the tacking strip in itself is inherently objectionable as a rather insec-40ure way of resisting the unusual vertical pulling stresses in a seat spring for a vehicle.

40 In the drawings, Figure 1 is a fragmentary perspective of the border strip showing it pinching the lower coil of one of the helical springs and the skirt of the upholstery. Fig. 2 is a similar view showing a modified 45 form. Fig. 3 is a plan view showing how the border strip is assembled to engage the upholstering skirt.

a designates the border strip which is made up of a foundation strip having a 50 lower doubled flange U-shape in cross section and opening inwardly so that it may be pinched over the bottom coil b of the helical spring. A vertical continuation of the flange already alluded to may be called the

web portion. This web portion terminates 55 at the top in an edge which is bent outwardly and then upwardly, the last bend forming the lip c and the first bend co-operating with the structure now to be described in forming a channel.

60 The second part of this two-part border strip comprises a web d which can be laid against the web of the foundation strip and which at its top is bent outwardly a little more sharply than the web of the foundation 65 strip is bent inwardly, then vertically, and finally outwardly to form the lip e. These two bends of the webs form a channel with a restricted opening when the two webs are riveted together, as shown in Fig. 1, by 70 gromets f, or when they are fastened together as shown in Fig. 2 by striking tongues 75 out of one member which can be bent back through perforations in the other member. In this channel groove the lower edge of the 80 upholstering skirt g may be pinched, as it is ordinarily provided with a sewed-in cord which makes the lower edge wider so that it may be easily gripped in a channel having a restricted opening.

85 In case it is desired to take the skirt out at any time, the gromets f can be easily removed with a suitable tool or the turned-over tongues can be bent back into perpendicular position to allow the disassembly 90 of the two webs.

In Fig. 3 the preferable way of making the complete assembly is shown. The inner, or what is termed the foundation part of the border strip, can be made in two pieces, 95 or for that matter it can be made in a single piece bent to form the complete rectangle necessary to encompass the entire cushion. The outer, or what might be termed the removable part of the border 100 strip can be made up of a pair of strips bent at each end to engage around the ends of the cushion and which strips are roughly shallow U-shape. These strips can be used to form the long sides of the border strip 105 and may be supplemented by a pair of short strips to complete the rectangle at the ends. These, as already alluded to, can be fastened to the foundation strip in the manner already described.

110 The spring seat is manufactured by the spring maker with the foundation strip attached and the removable strips are sent

to the automobile manufacturer or trimmer who rivets them on when the upholstering is in place.

What I claim is:

- 5 1. A border strip for spring cushions, having in combination, a foundation strip having a doubled flange at its bottom for securing the helical springs in place provided with a vertical web, and a removable 10 part secured to the foundation strip and comprising a web and a bent over portion at the top which coöperates with the top of the foundation in pinching the upholstering skirt removably in place.
- 15 2. A border strip for spring cushions, having in combination, a foundation strip comprising a web bent over at its top to form part of a channel and having means at its bottom to secure the helical springs 20 in place, and a removable part comprising a web adapted to be clamped to the web of the foundation strip and provided with a bent over portion at the top forming a part of the said channel, said channel operating to pinch the upholstering skirt in place.
- 25 3. A border strip for spring cushions, comprising a foundation strip in the form of a web bent at its top to form part of a

channel and doubled upon itself at the bottom to form a helical spring-retaining channel and a removable part comprising a web adapted to abut the web of the foundation strip and the bent-over portion at the top forming the other part of the said channel and a restricted opening therefor, and means for removably clamping the two webs together so the upholstering skirt can be removably held along its lower edge in the channel with the restricted opening.

4. A border strip for spring cushions, having in combination, a foundation strip comprising a vertical web having means at its bottom to secure the helical springs in place, and a removable strip comprising a vertical web, one of the said strips being provided at its top edge with a longitudinal corrugation which when in place forms with the top portion of the other strip a groove with a restricted opening to hold the bottom of the upholstering skirt, the said removable strip being adapted to be removably secured to the foundation strip, substantially as described.

In testimony whereof, I sign this specification.

BERT E. ROCKHOFF.
